United States Patent Office

Des. 210,777
Patented Apr. 16, 1968

210,777

TELEPHONE STAND

Henry Dreyfuss, South Pasadena, Calif., assignor to Bell Telephone Laboratories, Incorporated, Murray Hill, Berkeley Heights, N.J., a corporation of New York

Filed July 3, 1967, Ser. No. 7,691

Term of patent 14 years

(Cl. D26—14)

FIG. 1

FIG. 2

FIG. 3

FIG. 1 is a front perspective view of a telephone stand showing my new design;

FIG. 2 is a side elevational view, to a reduced scale and partially in cross section, of the telephone stand shown in FIG. 1; and

FIG. 3 is an end elevational view, to a reduced scale, of the telephone stand shown in FIG. 1.

The telephone handset shown in broken lines is for illustrative purposes only.

I claim:

The ornamental design for a telephone stand, substantially as shown and described.
